TOOTH ARRANGEMENT FOR SCREW TYPE
COMMINUTING DEVICES

Christian Börner, Obernburg (Main), Germany,
assignor to Vereinigte Glanzstoff-Fabriken
A. G., Wuppertal-Elberfeld, Germany

Application June 24, 1952, Serial No. 295,205
In Germany June 25, 1951

7 Claims. (Cl. 241—255)

1

The present invention relates to comminuting devices.

More particularly, the present invention relates to toothed members which are adapted to be mounted in screw type comminuting devices.

It has been found that screw type comminuting devices which are provided with toothed members to aid in the comminuting process do not generally provide the best possible results because the teeth within these devices are of a uniform size and do not provide a product having particles of the desired fineness.

It is the general object of the present invention to overcome this latter disadvantage by providing screw type comminuting devices of the above type with novel toothed members which greatly improve the comminuting action and produce a product which has very fine particles.

With this object in view, the present invention mainly consists of an apparatus including a cylindrical casing provided with an inner toothed surface, an inlet end and an outlet end, and a pair of opposite end walls. A screw member is located within this cylindrical casing, extends along the length thereof, and is mounted on the end walls of the casing for rotation about the axis of the latter. A plurality of pairs of opposite wall portions are fixed to the screw member between convolutions thereof to form separate chambers with said convolutions, the wall members on each side of said axis terminating in edge portions located along a straight line substantially at the outer periphery of said screw member and extending across the convolutions thereof in a direction parallel to the axis of said casing. A pair of elongated strips are fixed to the screw member and respectively extend along these lines, these strips each having a plurality of teeth formed along a free outer elongated edge thereof and gradually diminishing in size in a direction extending from the inlet to the outlet end of the casing. These elongated strips may have end portions adjacent to the inlet end of the casing provided with straight cutting edges.

The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a perspective, side sectional view of one possible apparatus for carrying out the present invention; and

2

Fig. 2 is a side view of a toothed strip constructed in accordance with the present invention.

Referring now to the drawings and more particularly to Figure 1, there is shown a cylindrical casing 1 having an inner surface provided with pyramidal teeth 2 and inlet and outlet ends respectively located at the right and left end portions of the casing, as viewed in Figure 1. 5 On opposite end walls of the casing there is rotatably mounted, for turning movement about the axis of the casing, a screw 3 having fixedly connected thereto opposite wall portions 5 which form separate chambers with the convolutions 10 of the screw 3, the first of these chambers being indicated by numeral 7. These walls 5, on each side of the casing axis, have free outer edges located along a straight line, and a pair of toothed members 4 are fixed to the worm 3 and 15 extend along these straight lines, these toothed members 4 being spaced from the pyramidal teeth 2 on the inner surface of casing 1 by a gap 6.

As is shown most clearly in Figure 2, each of 20 toothed strips 4 is provided with teeth which gradually diminish in size in a direction extending from the inlet to the outlet end of the casing 1. Also the toothed strips 4 are provided with straight cutting edges 8 at the end portions thereof adjacent to the inlet end of the casing 1.

25 The above described apparatus operates as follows:

Material to be comminuted is supplied to the 30 interior of casing 1 through the inlet thereof and enters the first chamber 7 and then moves toward the outlet end of the casing, successively entering the several chambers formed by the convolutions of the screw 3 and the walls 5. As the material moves toward the outlet end of the 35 casing, it is first broken up in a relatively coarse manner by the cutting edges 8 of the toothed strips 4. Then the material, upon passing through the gaps 6, is more finely divided by the 40 relatively large teeth of the toothed strips 4, and as the material approaches the outlet end of the casing 1, the smaller sized teeth gradually break up the material being comminuted to an increasingly greater extent so that the material finally emerging from the outlet of casing 1 is very finely divided.

45 It will be understood that each of the elements described above, or two or more together, may also find a useful application in other types of screw type comminuting devices differing from the types described above.

50 While I have illustrated and described the in-

vention as embodied in screw type comminuting devices adapted to very finely divide the material being comminuted, I do not intend to be limited to the details shown, since various modifications and structural changes may be made without departing in any way from the spirit of my invention.

Without further analysis, the foregoing will so fully reveal the gist of my invention that others can by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What I claim as new and desire to secure by Letters Patent is:

1. A screw type comminuting apparatus comprising, in combination, a cylindrical casing having an inlet end and an outlet end; a screw located within said cylindrical casing, extending along the axis thereof, and being mounted on said cylindrical casing for rotation about said axis; and an elongated toothed strip fixedly connected to said screw at the outer surface thereof and extending in a direction substantially parallel to said axis, said strip being provided with a plurality of teeth which are of a larger size at a portion of said strip adjacent to said inlet end of said casing than at a portion of said strip adjacent to said outlet end of said casing.

2. A screw type comminuting apparatus as defined in claim 1 and wherein a second strip identical with said first mentioned strip is located opposite the latter on said screw member.

3. A screw type comminuting apparatus as defined in claim 1 and wherein the teeth of said strip gradually diminish in size in a direction extending from the inlet end of said casing to the outlet end thereof.

4. A screw type comminuting apparatus as defined in claim 3 and wherein said strip is provided

with a straight cutting edge at the end portion thereof adjacent to the inlet end of said casing.

5. A screw type comminuting apparatus as defined in claim 1 and wherein said strip is provided with a straight cutting edge at the end portion thereof adjacent to the inlet end of said casing.

6. A screw type comminuting apparatus comprising, in combination, a cylindrical casing having an inner toothed surface, an inlet end and an outlet end, and a pair of opposite end walls; a screw member located within said cylindrical casing, extending along the length thereof, and being mounted on said end walls for rotation about the axis of said cylindrical casing; a plurality of pairs of opposite wall portions fixed to said screw member between convolutions thereof to form separate chambers with said convolutions, the wall members on each side of said axis terminating in edge portions located along a straight line substantially at the outer periphery of said screw member and extending across the convolutions thereof in a direction parallel to said axis; and a pair of elongated strips fixed to said screw member and respectively extending along said lines, said strips each having a plurality of teeth formed along a free outer elongated edge thereof, and said teeth gradually diminishing in size in a direction extending from the inlet to the outlet end of said casing.

7. Apparatus as defined in claim 6 and wherein in each of said strips is provided with a straight cutting edge at the end portion thereof located adjacent to the inlet end of said casing.

CHRISTIAN BÖRNER.
